MIXTURE CONTROL

Robert K. Thompson and Keith E. Dixon, Detroit,
Mich., assignors to George M. Holley and Earl
Holley

Application October 18, 1943, Serial No. 506,764

1 Claim. (Cl. 261—69)

The object of this invention is to control the mixture ratio in a variable Venturi carburetor so that the mixture ratio is maintained at the desired value when the throttles are opened and closed, when the altitude varies and when the air-flow varies independently of altitude and throttle position. The figure shows diagrammatically the preferred form of our invention.

In the drawing, the air entrance 10 supplies air to a mixture outlet 11 controlled by a pair of throttles 12 and 13, which, between them, form a variable venturi. These throttles are connected by gears 14 and 15, which gears 14 and 15 are driven by the gear 16 which is rotated by the drive-shaft 17 on which is mounted the cam 18. This cam 18 engages with the roller 19 and thus moves the needle 20 as the throttles are opened.

The fuel enters through a passage 21, flows through a diaphragm chamber 50, formed by the diaphragms 51 and 52, along passage 23 through an orifice 24 which is controlled by the valve 20. The fuel then descends in passage 25 and escapes through the openings 26 and 27 into the throat of the variable venturi, formed by the two throttles 12 and 13. The average value of the pressure in the air entrance is obtained at the number of openings 28 and 29 which communicate with a channel 30. This channel 30 communicates through a restricted opening 31 with passage 25, which passage provides air for atomizing the fuel in passage 25. This passage 25 communicates through an opening 32 with a chamber 33 which is separated from an atmospheric chamber 34 by a diaphragm 35. This diaphragm 35 is subjected to the pressure in the air entrance 10 through the openings 36 and 38. The opening 37 insures a circulation of air in the chamber 34 in which is located the partially evacuated barometric elements 39. This element is thus adapted to respond to changes in atmospheric pressure and changes in temperature. A needle 40 is moved by the diaphragm 35. The upper part of needle 40 is hollow and the lower portion has a negative taper which controls the opening 41. As the valve 40 is hollow and is notched at its upper end, it provides an unrestricted communicating passage from the orifice 41 to the chamber 33. This opening 41 communicates with a passage 42 and thus with the chamber 43 which is connected to the chamber 44. These air chambers are located to the right and left-hand sides of the diaphragms constituting the diaphragm chamber 22 and thus these air chambers control the pressure under which the fuel flows in passage 23 in a well known manner. Passage 42 communicates with the

channel 30 through a restriction 45. The diaphragm 35 is supported by the spring 46 and a smaller spring 47 which holds the needle valve 40 pressed against the diaphragm 35. This is to prevent the needle 40 from binding in its guide. A compression spring 48 separates the barometric element 39 from the diaphragm 35 and opposes the two springs, 46 and 47. In order that the level in the diaphragm chamber 50 may be as high as possible without flooding, a spring 49 may be used to adjust the level when the engine is not running.

Operation

When the throttles are open in the position 15 shown by means of an anti-clockwise rotation of the shaft 17, the increased airflow through the variable venturi causes fuel to flow past the restriction 24. The quantity of fuel flowing is determined by the cam 18 which determines the 20 opening between the needle 20 and the restricted orifice 24. There is thus a mechanical connection between the opening of the air passage and the opening of the fuel passage. Such an arrangement would be satisfactory on a marine engine 25 where every position of the throttle corresponds to a definite number of revolutions per minute of the engine. Obviously, in an airplane with a variable pitch propeller we can change the load and the altitude so we therefore have to correct for 30 varying loads and varying altitudes. It is also desirable to correct for varying temperatures as an increase of temperature decreases the density of the air just as an increase in altitude. Hence the 35 valve 40 responds to the increases and decreases in temperature and pressure. This varies the opening through the orifice 41 and therefore more or less of the suction in the passage 25 is transmitted to the chambers 43 and 44 through the hollow needle 40. The variation in load which occurs when the pitch of the propeller is changed is transmitted to the diaphragm 35 which responds to the difference of pressure between the air entrance and in the throat of the venturi. The 40 needle 40 therefore responds to variations in both 45 load and altitude.

We have found that it is possible to correct and to maintain the mixture within the desired limits by means of the shape of the needle 40. The orifice 45, when the orifice 41 is closed by the needle 40, is able to subject chambers 43 and 44 to atmospheric pressure or pressures substantially equal thereto. The barometric element 39 responds to changes in the atmospheric pressure, the diaphragm 35 responds to changes in the drop 50 in pressure in the throat of the venturi, and these 55

two elements 38 and 35 are coupled together so as to vary the position of the valve 40 in the orifice 41. The relative area of the variable orifice 41 to the fixed orifice 45 determines the pressure in the chambers 43/44.

What we claim is:

A variable Venturi carburetor, an air entrance, a fuel entrance adapted to discharge into the throat of said variable venturi, a fuel supply chamber having a moving wall, an air chamber associated with said moving wall, an air pressure regulating chamber, a diaphragm therein dividing said air pressure regulating chamber into an atmospheric chamber connected to the air entrance

and a sub-atmospheric chamber connected to the throat of said variable venturi, barometric means located in said atmospheric chamber spring means interposed between said diaphragm and said barometric means, a passage connecting said sub-atmospheric chamber with the first-mentioned air chamber, a restricted air entrance into said passage, valve means operatively connected to said diaphragm, spring and barometric means and adapted to control the connection of said passage with said sub-atmospheric chamber.
